UNITED STATES PATENT OFFICE.

WILLIAM KELSO, OF PITTSBURGH, PENNSYLVANIA, ASSIGNOR TO THE MC CONWAY & TORLEY COMPANY, OF PITTSBURGH, PENNSYLVANIA, A CORPORATION OF PENNSYLVANIA.

CAR COUPLER.

Application filed January 31, 1923. Serial No. 616,123.

To all whom it may concern:

Be it known that I, WILLIAM KELSO, a citizen of the United States, residing at Pittsburgh, in the county of Allegheny and 5 State of Pennsylvania, have invented certain new and useful Improvements in Car Couplers; and I do hereby declare the following to be a full, clear, and exact description of the invention, such as will enable 10 others skilled in the art to which it appertains to make and use the same.

My invention relates to car couplers of the Master Car Builders' type and particularly to the form known as the standard D-coupler. While the improvements hereinafter described and claimed are especially applicable to the D-coupler, it is to be understood that they are not limited in their application to that form of coupler alone. 20 The principal object of the invention is to provide a lock lifter for a coupler of the D-type which may be readily assembled with the other parts of the mechanism, which cannot accidentally drop or be forced to a position 25 precluding it from performing its intended function of moving the lock to unlocked position, which is efficiently strengthened, and is provided with means for deflecting shearing blows such as the lifter may 30 accidentally receive in service by reason of heavy objects falling upon its upper end.

The primary feature of the invention, generally stated, consists in combining with a coupler head and the knuckle pivotally 35 mounted thereon, an upwardly movable and rearwardly swinging lock for the knuckle adapted to be actuated by a lock lifter whose lower end is provided with trunnions extending into an upwardly and rearwardly opening 40 slot with which the lock is provided, the upper wall of the coupler head being formed with an opening adapted to permit the passage of the said trunnions, and the upper end of the lifter being formed with a shoulder 45 overlapping the top wall of the said head and adapted to engage the same to limit downward movement of the lifter.

A further feature of the invention consists 50 in providing a lock lifter having trunnions at its lower end with laterally extending flanges projecting into and movable through an opening in the top wall of the coupler head through which the lower end of the

lifter may pass, the said flanges providing means when the parts are in locked position 55 for closing the portions of the opening in the coupler head corresponding to the trunnions of the lifter.

Still another feature of the invention consists in providing the lock lifter at its upper 60 end with a lug overlapping the top wall of the coupler head, the upper surface of the said lug being inclined downwardly and preferably toward the forward end of the coupler. 65

Other features of the invention residing in special details of construction and in the relations of parts will hereinafter appear and be pointed out in the claims.

In the drawings illustrating the invention 70 as applied to a Master Car Builders' standard D-coupler,

Figure 1 is a vertical sectional view of mechanism involving the invention, the lock, knuckle opener, knuckle and lock lifter being 75 in elevation and in locked relation.

Figure 2 is a detail plan view of the upper end of the lock lifter and the adjacent portion of the coupler head.

Figure 3 is a detail view in rear elevation 80 showing the lock lifter.

Figure 4 is a side elevation of the lock lifter.

Figure 5 illustrates a modified form of lock lifter embodying the invention, the upper portion of the lifter being in elevation and the adjacent portion of the coupler head in vertical section. 85

Figure 6 is a view corresponding to Fig. 5 but illustrating a further modification of 90 the lock lifter embodying the invention.

In the D-coupler the knuckle is normally retained in locked or coupled position by means of an upwardly movable and rearwardly swinging lock. Where these 95 couplers are applied to freight cars this lock is customarily actuated by a lock lifter extending upwardly from the lock through an opening in the top wall of the coupler head, the lower end of the lifter being provided with trunnions entering an upwardly and rearwardly opening slot in the lock and constituting means for slidably and detachably connecting the lock and lifter. At its upper end the lifter is operatively 100 attached to a suitable uncoupling rod or

release mechanism for enabling the trainman from a position at the side of the car to operate the lifter so as to produce the movements of the lock required to release 5 the knuckle and effect its outward rotation. In normal or locked relation the lower end of the lock lifter projects rearwardly beyond the lock so as to stand beneath a shoulder or anti-creep lug fashioned upon 10 the inside of the coupler head. This relation of the lower end of the lifter to the anti-creep lug is designed to prevent the coupler lock from accidentally moving to an unlocked position. As a result of service, however, the parts of the coupler are 15 reduced in size by wear and become capable of assuming positions detrimental to effective operation of the device. As at present constructed the association in the D- 20 coupler of a worn lock lifter with a coupler head in which the anti-creep lug is of reduced length permits the lock lifter to drop below its normal position, thereby allowing its trunnions to pass out of the lifter 25 receiving slot of the lock. When the lifter has assumed such a relation the uncoupling lever or release rigging mechanism is ineffective to induce an unlocking movement 30 of the lock. If it becomes necessary under such circumstances to unlock the coupler the trainman is required to stand between the cars where he can reach the lifter and then to endeavor by careful manipulation to work the trunnions of the lifter back 35 into their operative position in the slot of the lock. It is in this manner at times possible to restore the lifter to a position enabling the lock to be operated by actuating the coupler release rigging in the usual 40 way; but if the trainman cannot thus cause the lifter to be returned to a position in which its trunnions are within the slot of the lock and its lower end is retracted from beneath the anti-creep lug of the coupler head, it becomes necessary to cut or otherwise 45 destroy the knuckle or other parts of the mechanism before the coupler can be dismantled. Moreover, where a worn lock lifter is associated with a coupler head having a short anti-creep lug the disconnection 50 of the uncoupling rod or release rigging from the lifter may, unless care is taken, result in allowing the lifter to drop and pass wholly within the coupler head. In 55 such a case also parts of the mechanism must be destroyed in order to separate parts of the coupler.

By my invention these undesirable effects are obviated and the lock lifter is 60 prevented under all circumstances from assuming an inoperative relation to the lock. This improvement in the D-coupler is accomplished, as will hereinafter appear, in a manner permitting advantageous lateral 65 strengthening of the lock lifter as well as

the provision of simple means for deflecting such accidental shearing blows as the lock lifter is ordinarily liable to receive.

In the drawings 1 is the coupler head and 2 is the knuckle rotatably mounted 70 thereon by means of the usual knuckle-pin 3. The knuckle is maintained in closed or coupled position by means of the well known form of locking block 4 having a depending leg 5 which projects downwardly through 75 an opening 6 in the lower wall of the coupler head. The lock 4, which is brought into assembled relation with the coupler head 1 by being introduced through the mouth 7 of said head, is capable of sliding vertically and swinging rearwardly, the former movement effecting the release of the knuckle and the latter enabling the depending leg 5 to press rearwardly against and rotate the standard form of knuckle opening lever 8 85 so as to cause an uncoupling rotation of the knuckle. As shown in the drawings, the lock 4 is seated upon the pivoted knuckle opening lever 8 when the parts are in locked relation. 90

The coupler lock 4 is caused to perform its unlocking and knuckle throwing movements by means of a lifter member 9 which, instead of being brought to assembled position by introducing it through the mouth 95 of the coupler, as is the case when the lifter is of the standard form, is brought into operative relation to the lock by entering its lower end through an opening 10 in the upper wall of the coupler head. 100

The lower end of the lifter 9 may and preferably does conform to the usual details of construction of the top lift member of the D-coupler, being provided with oppositely disposed laterally projecting trunnions 11 105 extending into the upwardly and rearwardly opening slot 12 in the upper end of the lock 4 and constituting means for movably and detachably connecting the lifter to the lock. When the parts are in locked or normal position the face or shoulder 13 at the lower end of the lifter 9 stands beneath the anti-creep lug 14, thus preventing the lock from performing an unlocking operation until, by an upward pull upon the lifter, the shoulder 13 is withdrawn from beneath said lug 14. 110

The lifter receiving opening 10 in the top wall of the coupler head is preferably of T-form, its oppositely disposed branches or 115 recesses 15 permitting the passage of the corresponding trunnions 11. At its rear intermediate of its ends the lock lifter 9 may advantageously be provided with laterally extending flanges 16 whose upper ends project into the respective recesses 15 through which the trunnions are entered and thus provide means for closing said recesses when the parts are in locked position. The remainder of the aperture 10 is normally 120 125 130

closed by the forward portion of the lifter 9, as will readily be understood upon reference to Fig. 2. The extended flanges 16 projecting into and movable through the recess 15 impart highly desirable lateral stiffness to the rearward portion of the lock lifter.

To insure the maintenance of an operative relation of the lock 4 and lock lifter 9, and to prevent the lifter from dropping or being forced completely into the coupler head, the upper end of the lifter is provided with a lug or shoulder 17 which overlaps the upper wall of the coupler head and by engagement therewith serves to limit downward movement of the lifter. The lug 17 is preferably located at the forward side of the lifter and its upper surface 18 is inclined, sloping downwardly away from the opening 10 toward the forward end of the coupler so as to deflect any shearing blow imparted to the lifter from the direction from which such blows are ordinarily received. An eye 19 in the upper end of the lifter affords suitable means for operatively connecting it to an uncoupling rod or other release rigging mechanism. To permit the passage of the lower end of the lifter through an opening 10 of minimum size, the top wall of the coupler head is preferably undercut slightly on opposite sides of said opening, as indicated at 20.

As shown in the modified form of the invention illustrated in Fig. 5, the means for limiting the downward movement of the lock lifter may take the form of a lug 21, corresponding to the lug 17 but extending rearwardly instead of forwardly; and, as shown in Fig. 6, both a forwardly extending lug 17 and a rearwardly extending lug 21 may be employed jointly. As the constructions disclosed in Figs. 5 and 6 are in other respects identical with features heretofore described, corresponding parts have been indicated by the same reference numerals.

I claim:—

1. In a car coupler, the combination with a coupler head, of a knuckle pivotally mounted thereon, an upwardly movable and rearwardly swinging lock for said knuckle, and a lock lifter for actuating said lock, said lock being formed with an upwardly and rearwardly opening slot adapted to receive the lower end of said lifter, said lifter being detachably connected to said lock by trunnions formed on said lifter and extending into said slot, the upper wall of said coupler head being formed with an opening adapted to permit the passage of said trunnions and through which the upper end of said lifter projects, and the upper end of said lifter being provided with a shoulder adapted to engage the upper wall of said coupler head to limit downward movement of said lifter.

2. In a car coupler, the combination with

a coupler head, of a knuckle pivotally mounted thereon, an upwardly movable and rearwardly swinging lock for said knuckle, and a lock lifter for actuating said lock, said lock being formed with an upwardly and rearwardly opening slot adapted to receive the lower end of said lifter, said lifter being detachably connected to said lock by trunnions formed on said lifter and extending into said slot, the upper wall of said coupler head being formed with an opening adapted to permit the passage of said trunnions and through which the upper end of said lifter projects, and said lifter being flanged at its rear to provide means for normally closing the portions of said opening adapted to permit the passage of said trunnions.

3. In a car coupler, the combination with a coupler head, of a knuckle pivotally mounted thereon, an upwardly movable and rearwardly swinging lock for said knuckle, and a lock lifter for actuating said lock, said lock being formed with an upwardly and rearwardly opening slot adapted to receive the lower end of said lifter, said lifter being detachably connected to said lock by trunnions formed on said lifter and projecting into said slot, the upper wall of said head being provided with a T-shaped opening adapted to permit the passage of said trunnions, and said lifter being provided at its rear with laterally extending flanges which when said lifter is actuated project into and are movable through the portions of said opening corresponding to said trunnions.

4. In a car coupler, the combination with a coupler head of a knuckle pivotally mounted thereon, an upwardly movable and rearwardly swinging lock for said knuckle, and a lock lifter for actuating said lock, said lifter being detachably connected to said lock by trunnions formed on said lifter, and the upper wall of said head being formed with a T-shaped opening adapted to permit the passage of said trunnions.

5. In a car coupler, the combination with a coupler head, of a knuckle pivotally mounted thereon, a lock for said knuckle, and a lock lifter detachably connected to said lock so as to be movable with respect thereto, the upper wall of said head being formed with an opening adapted to permit the passage of the lower end of said lifter, and the upper end of said lifter having rigidly connected thereto a lug adapted to engage the upper wall of said head to limit the downward movement of said lifter, the upper surface of said lug being inclined.

6. In a car coupler, the combination with a coupler head, of a knuckle pivotally mounted thereon, a lock for said knuckle, and a lock lifter slidably connected to said lock, said lock being formed with a slot into

which the lower end of said lifter extends, the upper wall of said head being provided with an opening adapted to permit the passage of the lower end of said lifter, and the upper end of said lifter being formed with a lug adapted to engage the upper wall of said head to limit the downward movement

of said lifter, said lug having an upper face which slopes downwardly toward the forward end of the coupler.

In testimony whereof I affix my signature.

WILLIAM KELSO.
